UNITED STATES PATENT OFFICE

2,567,298

WATERPROOF FASTENER

Hans G. Morner and Eric J. Fredsell, New York,
N. Y.; said Fredsell assignor to said Morner

Application January 4, 1945, Serial No. 571,290

8 Claims. (Cl. 24—203)

1

The invention pertains to separable fasteners, and has as its primary object the provision of a fastener which can easily and rapidly be opened and closed.

Other objects and advantages of the invention will appear from the following description and will be obvious therefrom or may be learned by use of the invention and are attained by utilization of the construction hereinafter described and illustrated in the accompanying drawings or by constructions which are an equivalent thereof.

In some respects the invention comprises an improvement over the fasteners disclosed in the H. G. Morner Patents No. 2,306,488 dated December 29, 1942, and 2,355,816 dated August 13, 1944.

The fastener is susceptible of use in many and diversified manners and arts but is particularly well adapted as a closure fastener for use with life-saving suits, rafts, water-proof provision bags and other containers and particularly where a separable closure which is required to be liquid and gas-tight is required and where the closure must be such that it can be easily, readily and rapidly operated for opening and closing. The invention is well adapted for use in connection with footwear and particularly rubber shoes and boots or foot coverings of a water-tight and water-proof nature.

In the referred to Patent No. 2,306,488 the fastener therein is particularly described and illustrated in connection with a life-saving and protecting suit and in the present application the fastener is equally adaptable for such use, but it is to be understood that the invention is not limited to such a specific use or necessarily in connection or combination with a liquid or gas-tight closure seam but is to be limited only within the scope of the hereinafter following and appended claims.

In the drawings wherein one embodiment of the invention is illustrated:

Fig. 1 is a fragmentary front view illustrating one form and embodiment of the invention, a portion of the view being broken away to more clearly illustrate the construction.

Fig. 2 is a transverse sectional view on the line 2—2 of Fig. 1 looking in the direction indicated by arrows.

Fig. 3 is a vertical sectional view taken on the line 3—3 of Fig. 1, looking in the direction indicated by arrows.

Fig. 4 is a detail perspective view of the two-part fastener, the parts being illustrated in their engaged or closed positions.

2

The particular embodiment of the invention illustrated in the drawings and about to be described is that of a liquid and gas-tight type of closure such as is illustrated in the before referred to Morner patents, and with the exception of the closure fastening means the present invention is closely similar in construction to the inventions of said patents.

The terminal portions of a sheet comprising the 10 particular article or item provided with a closure are designated A and B. These portions constitute the opposite side edges of an opening and are to be secured together when it is desired to close the opening. The opening to be closed is 15 designated 1.

Inasmuch as the closure is of the liquid and gas-tight type the material of which A and B are the 20 terminal ends would in all probability be of a flexible and water-proof nature such as for instance rubber, a rubber covered or impregnated fabric or an otherwise suitably water-proofed fabric. It is to be recognized however that the invention is not limited to the particular nature of the material in which the opening 1 is provided.

25 A flexible rubber strip extends throughout the length of the edges of each of the terminal portions A and B. For convenience in description these will be referred to as male and female strips and are designated generally as C and D. These strips are substantially identical to the strips of the recited issued Morner patents. Each strip is composed of relatively thick but pliable and yieldable rubber which is preferably about the consistency of automobile tire rubber or slightly 30 softer. The strips are therefore inherently flexible throughout their lengths and are thus adapted to conform to the shape of the container and its contents and can be bent by the application of a slight amount of physical force.

35 40 The male strip is formed with a flat base portion 2 of tapering thickness to terminate in a thin side edge portion 3. The base is adapted to be seated on and vulcanized or otherwise suitably secured to the terminal edge B of the sheet. Preferably although not necessarily a sealing flap 4 is provided and overlies the upper face of the strip base. The flat base portion 5 of the female strip D is similarly formed and secured to the 45 terminal portion A of the sheet.

50 The female strip D is provided with a socket or groove 6 which is coextensive with the strip length. This socket or groove is formed by an upper node or ridge 7 the terminal end or edge of which is arcuate and by a lower node or ridge 55 8 which curves upwardly and outwardly to pro-

vide an upper terminal edge 9. The under face of the upper node and the upper face of the lower node are positioned more closely to one another than the maximum cross sectional diameter of the socket 6 to provide for said socket a mouth or entrance which is of reduced cross section in respect to the interior cross section of the groove. The upper and outer surface of the strip is curved or rounded as at 10. The under surface of the lower node is provided with a shoulder 11 the purpose of which will hereinafter appear.

The male strip is provided throughout its length with a node 12 which is shaped and dimensioned to snugly fill the groove or socket 6 in the female strip. This node is provided with a neck portion of reduced thickness so as to conform to and fit tightly in the space between the extending ends of the upper and lower nodes of the female strip which constitute the entry into the socket of said strip. The male strip is shaped to provide upper and lower sockets for the reception of the upper and lower nodes of the female strip as clearly appears from Fig. 2 of the drawings. The top wall of the upper socket is of tapering thickness to provide a relatively thin lip portion 13 overlapping and overlying the upper node of the female strip. The lower wall of the lower socket is likewise of tapering thickness to provide an overlapping and underlying lip 14 beneath the lower node of the female strip and the terminal edge of the lip 14 abuts the shoulder 11 on the under face of the lower node 8 of the female strip.

The interlocked relationship of the strips clearly appears in Fig. 2 of the drawings. The strips which are yieldable and compressible because of the material of which they are composed can be readily, easily and quickly forced into interlocking relationship with one another by the application of a very limited amount of physical pressure. The strips will however, when they are locked and securely held in interlocking relationship, provide a liquid and gas-tight joint for the closure. The present invention specifically pertains to the provision of a fastening means for securing the strips in locked interlocking relationship and the provision of a fastening means which is automatically locked when the strips are forced into interlocking relationship yet constitute a fastener which can be quickly and unfailingly rapidly released when desired.

The strip or closure locking or fastening means per se is illustrated in Fig. 4 of the drawings and in general comprises two wires, each of which extends throughout the length of one of the closure strips and which are so shaped as to cooperate with one another in the accomplishment of the recited desired results.

In the particular embodiment of the invention illustrated each of the wires which for convenience in description are designated generally as E and F is of continuous length. It is to be understood however that if it should for any reason be desired each fastener could be individually formed. The use of a continuous wire for each strip has decided advantages in simplifying and reducing the cost of manufacture of the fasteners and simplifying and reducing the cost of fabrication of the finished and complete closure. By making the fasteners in the form of continuous wires the positioning of the wires on the closure strips for proper locking and releasing cooperation with one another is practically automatic whereas this would not be the case were each fastener individually formed and

individually applied or secured to its respective closure strip.

To facilitate the description of the fasteners they, like the strips, will be referred to as male and female. The male portion of the fasteners is designated E and is associated with the male strip C, and the female portion of the fasteners is designated F and is associated with the female strip D.

Referring to Fig. 4 which illustrates one individual fastening and having reference to the male fastener, it will be seen that it comprises a pair of spaced in line legs 15 and 16 from the adjacent ends of which extend outwardly a pair of spaced parallel arms 17 and 18 the outer ends of which are connected by a cross arm which has an upwardly and slightly rearwardly extending portion 19 terminating in a rounded nose 20 from which extends a downwardly and outwardly curved portion 21. The nose 20 provides a hook, as will hereinafter more fully appear, in that the particular shaping of the cross arm provides an overhang to form a seat 22. The nose or hook 20 is disposed in a plane above, or below, dependent upon how the element is viewed, the arms 17 and 18.

The female portion F of the fastener comprises a pair of in line legs 23 and 24 from which extend outwardly spaced and parallel arms 25 and 26 which have their outer ends bent upwardly as at 27 and have their outer ends joined by a straight cross arm 28. Due to the upward bend of the arms 25 and 26 the cross arm 28 lies in a plane above the legs 23 and 24 and the inner portions of the arms 25 and 26.

As is apparent from Fig. 4 of the drawings the cross arm 28 of the female portion is adapted to be positioned in the seat 22 of the male portion of the fastener and beneath the hook portion 20 of the male portion of the fastener when in tension.

The wire forming the fastener elements may be of a resilient nature and thus permit the wire to give in a resilient manner upon the application of a reasonable amount of physical force. This wire is preferably of spring steel or stainless steel of high tensile strength. As will appear hereinafter portions of the fastener may yield as the fasteners move into locked and unlocked relationship.

From the description thus far given it will be seen that with the catch made in the form of a pair of continuous wires there is a mere duplication of catch elements throughout the length of the wire. This appears most clearly from Fig. 1 of the drawings. To simplify fabrication of the closure the male and female elements of the catch are disposed upon the flat bases of the male and female strips respectively and are held in place when these bases are vulcanized or otherwise suitably secured to the terminal portions A and B. The proper positioning of the co-operating elements of one wire in respect to the other will automatically position all of the catch elements throughout the length of the closure. Should it for any reason be desired the wires could be actually within the rubber constituting the closure strips, being placed there at the time said strips are molded. The length of the legs 17 and 18 and 25 and 26 of the male and female portions respectively of the catches together with the positioning of the wires on the strips is such that when the strips are positioned in interlocking relationship the cross arm 28 of the female catch element will have passed over and then

directly under the nose or hook portion 20 of the male catch element, and then lies parallel with the legs 15 and 16.

The manner of operation of the catches is as follows. Assuming that the closure is open, closure thereof is effected by starting at the lower end of the closure and progressively pressing the strips C and D into interlocking relationship. In Fig. 1 of the drawings this operation is illustrated as having progressed throughout a portion of the length of the closure. Referring to this figure it will be seen that one of the catches is about to be moved into locked position. As the strips are pushed together the arm 28 of the female portion of the catch rides up the inclined portion 19 of the male portion of the catch and over the nose or hook portion thereof. As the arm 28 passes slightly beyond the hook, as it will upon tight compression of the closure strips, this arm snaps down beneath the hook and as the pressure is released upon the closure strips this arm moves under the hook into the position illustrated in Fig. 4 of the drawings where it is directly below 20 and is parallel with a line drawn through legs 15 and 16. This operation is repeated throughout the length of the closure and can be a very rapid one. As the closure is progressively closed the arms 28 can be heard to snap over and under the hooks 20.

When it is desired to open the closure this can be quickly, easily and rapidly accomplished. It is necessary only to grasp the base portions of the two strips and move them in opposite directions to one another in respect to their longitudinal axes or to hold one strip against movement and move the other strip. When the male strip is pulled away from the female strip the arm 28 moves upwardly along the inclined portion 19 and toward the hook 20. Continued movement in this direction will carry the arm 28 out of its seat and beyond the hook 20 to completely disengage the catch. If the female strip is held against movement and the male strip is moved the movement thereof must be in the opposite direction, that is, in a direction toward the arm 17 so that the hook portions 19 and 20 are progressed until they are moved below the arm 28 and are finally disengaged therefrom.

It is thought that in normal operation the tendency would be to firmly grasp the strips and move them in opposite directions, as first explained. This would accelerate disengagement of the catches which disengagement can be heard as the parts of the catch snap apart.

From the foregoing it will be seen that in opening the closure the fastened sides of the closure are suitably grasped and the sides of the closure are moved in a direction transverse the length of the closure. This might be described as imparting a ripping action to the closure, a ripping in a direction lengthwise of the closure.

In order to make the hooks engage it is necessary first to engage the rubber parts then by means of the legs on the slide the legs 25, 26 and 17, 18 are depressed in such a manner that arms 28 will easily pass over hooks 20.

In both the opening and closing operations the resilient and compressible nature of the rubber strips enables these strips to be quickly and easily pressed into interlocking engagement or disengaged from one another in accordance with the particular desire of the user.

In both the closing and opening operations of the closure there is a resilient cooperative action

between the male and female portions of the catch. The cross arm 19 of the male catch portion in addition to being inclined along its length slants or is slightly curved backwardly in a direction toward the legs 15 and 16. Thus as the strips are pressed into interlocking relationship the cross arm 28 of the female catch portion readily slides up and along the leg 19 and over the hook or nose 20. There is something similar to a cam action and there is some slight tendency for the cross arm 19 to be depressed as the cross arm 28 rides up and over it. When the closure is pulled or ripped open the under or rear surface of the cross arm 19 provides an inclined or cam-like face or surface which permits the cross arm 28 to readily move upwardly and outwardly to the extremity of the nose or hook 20 so as to snap over and past it to a released position. In this action there may be some give in both the cross arm 28 and the nose 20 although the greatest movement is a bowing of the cross arm 28 as pressure is exerted to pull this arm along and past the nose or hook 20. As to which gives the most as between the male and female portions of the catch would be dependent largely upon the exact direction of the pressure exerted by reason of the direction of the pull or tearing action exerted to open the closure.

From the foregoing description it will be seen that the catch can be described as comprising a hook and an eye. The hook is formed as the cross arm of the male catch portion and the eye comprises the female portion of the catch. It will be understood that for proper operation the male and female portions of the catch are preferably rigidly secured to their respective strips or to the particular element which carries them. Movement of the leg portions of the catch element would defeat the resilient action which is essential to the latching and unlatching operations.

It will also be seen that when the catch is used in combination with resilient strips the male and female catch parts can be so positioned as to cause the resiliency of the strips to more rigidly hold the catch in a locked position under resilient tension, if that be desired. If the strips are in a state of compression when the latch elements are in locked or latched relationship then there would be a tendency for the strips to separate under resilient tension. This resilient tension or force would tend to more forcibly hold the cross arm of the female catch portion in its seat under the hook of the male catch portion. This resilient tension, however, would not render it any more difficult to rapidly disengage the catch elements by pulling the parts, as described, when it is desired to open the closure.

The catches are at the inner side or within the closure which serves to protect them which is highly desirable where the catch is used in connection with a garment or articles used in salt water.

The invention in its broader aspects is not limited to the specific mechanisms shown and described but departures may be made therefrom within the scope of the accompanying claims without departing from the principles of the invention and without sacrificing its chief advantages.

We claim:

1. A fastener comprising, a hook and a member movable substantially unilinearly into engagement with and disengagement from said hook, an inclined cam-like surface at each side of said

hook, said hook engaging member adapted to ride said cam-like surfaces as the fastener is hooked and unhooked, said hook and said engaging member each being formed of resilient metal yieldable to permit hooking and unhooking by said rectilinear movement, said hook and said member being mounted on opposed and oppositely-movable inter-engaging strips of compressible material, said strips when inter-engaged being in a state of compression and exerting a resilient, interlocking force upon the hook and said member.

2. A fastener comprising a female member having a pair of parallel arms and a cross arm joining said parallel arms, a male member comprising a pair of parallel arms separated from each other by a smaller distance than the parallel arms of said female member and a cross arm joining said pair of parallel arms and extending upwardly from each of said parallel arms and reversibly back upon said arms so as to provide a guide for the movement of said female cross arm during the engaging operation and a clasp for said cross arm after engagement, said members being made of resilient material yieldable to permit engagement and disengagement by substantially rectilinear motion of the members toward and away from each other respectively, and means for constraining said members to such motion, said means including opposed and oppositely-movable, separable inter-engaging strips of compressible material, the female member being connected to one strip and the male member to the opposite strip, said strips when inter-engaged being in a state of compression and exerting a resilient, interlocking force upon the male and female members.

3. A fastener comprising a male member having a pair of parallel arms and a cross arm joining said arms and extending upwardly from said arms and folding back upon said arms as it extends upwardly and a female member having a pair of parallel arms spaced further apart than the parallel arms of said female member and a cross arm joining said parallel arms, said members being made of resilient material yieldable to permit engagement and disengagement by substantially rectilinear motion of the members toward and away from each other respectively, and means for constraining said members to such motion, said means including opposed and oppositely-movable, separable inter-engaging strips of compressible material, the female member being connected to one strip and the male member to the opposite strip, said strips when inter-engaged being in a state of compression and exerting a resilient, interlocking force upon the male and female members.

4. In a fastener of the character set forth in claim 3, each of the parallel arms of said female member inclined upwardly along part of its length adjacent the cross arm joining the parallel arms, for facilitating the locking engagement of said male and female members.

5. In combination, a fluid-tight closure including a pair of resilient, flexible strips forming male and female members, the male strip having a projecting node and the female strip having a groove shaped to conform to said male node and a pair of projecting lips defining said groove and fitting over said node on said male strip so as to grip said node, and a fastener for holding said strips in sealed relationship comprising in combination, a male member having a pair of parallel arms and a cross arm joining said arms and

extending upwardly from and folding back upon said parallel arms, and a female member having a pair of parallel arms spaced further apart than the parallel arms of said male member and a cross arm joining said parallel arms of said female member and engageable between the cross arm and parallel arms of said male member, said members being made of resilient material yieldable to permit engagement and disengagement by substantially rectilinear motion of the members toward and away from each other respectively, and means for constraining said members to such motion, said strips in sealed relationship being in a state of compression whereby to exert a resilient, interlocking engaging force upon said members.

6. In combination, a fluid-tight closure including a pair of resilient, flexible strips forming male and female members, the male strip member having a projecting node defined by a pair of grooved portions and the female strip member having a pair of projecting nodes defining therebetween a grooved portion conforming in shape to said male node, said female nodes fitting tightly into the grooves defining said male node, and a fastener for holding said strips in sealed relationship and comprising in combination a plurality of male members each having a pair of parallel arms and a cross arm joining said arms, said cross arm of each male member extending away from said parallel arms and simultaneously folding back upon said arms, and a plurality of female members each having a pair of parallel arms and a cross arm joining said parallel arms having a greater width than said associated male cross arm, said members being made of resilient material yieldable to permit engagement and disengagement by substantially rectilinear motion of the members toward and away from each other respectively, and means for constraining said members to such motion, said strips in sealed relationship being in a state of compression whereby to exert a resilient, interlocking engaging force upon said members.

45 7. In a fastening and sealing combination of the character set forth in claim 6, the male cross arm of each fastener extending upwardly from and in a skewed direction with respect to the parallel arms of said fastener and simultaneously folding back upon said arms so as to form a hook portion for guiding the movement of said female member during the engaging operation and for securing said female member after the completion of said engaging operation, and the parallel arms of said female member inclining upwardly in the portions adjacent the connecting cross arm for facilitating the movement of said female member up the hook portion of said male member.

60 8. In combination, a fluid tight closure including a pair of resilient, flexible strips forming male and female members, the male strip member having a projecting node and recessed portions defining said node, the tip portion of said node being wider than the tail portion, and the female strip member having a pair of projecting nodes defining a groove portion with a relatively narrow mouth and corresponding in shape to said node on said male member, and a fastener for holding said strips in sealed relationship and comprising a plurality of male and female members, the male members extending in series along the length of one of said strip members and the female members extending in series along the length of said other strip member, each of said

male members comprising a pair of parallel cross arms and a cross arm joining said arms and extending upwardly from and backwardly upon said parallel arms, and each of said female members comprising a pair of parallel arms separated from each other by a greater distance than the parallel arms of said male members and inclined along part of their length and a cross arm joining the inclined portions of said parallel arms, said male and female members each being formed of a continuous length of wire, said members being made of resilient material yieldable to permit engagement and disengagement by substantially rectilinear motion of the members toward and away from each other respectively, and means for constraining said members to such motion, said strips in sealed relationship being in a state of compression whereby to exert a resilient, interlocking engaging force upon said members.
